UNITED STATES PATENT OFFICE.

OLE H. MELLUM, OF UNION, NORTH DAKOTA.

WRENCH.

1,184,000.

Specification of Letters Patent. Patented May 23, 1916.

Application filed June 18, 1915. Serial No. 34,902.

To all whom it may concern:

Be it known that I, OLE H. MELLUM, citizen of the United States, residing at Union, in the county of Cavalier and State of North Dakota, have invented certain new and useful Improvements in Wrenches, of which the following is a specification, reference being had therein to the accompanying drawings.

10 This invention relates to a wrench and has for its principal object the production of a simple and efficient means for adjusting the sliding jaw whereby the various sized nuts may be easily accommodated when desired.

15 Another object of this invention is the production of a wrench wherein a simple and efficient means has been provided for positively retaining the sliding jaw in an adjusted set position when the device is in operation.

20 With these and other objects in view, this invention consists of certain novel combinations, constructions, and arrangements of parts, as will be hereinafter fully described and claimed.

25 In the accompanying drawing: Figure 1 is a side elevation of the wrench as constructed in accordance with this invention. Fig. 2 is a front elevation of the wrench. Fig. 3 is a section taken on the line 3-3 of Fig. 2. Fig. 4 is a section taken on the line 4-4 of Fig. 1, looking in the direction of the arrows. Fig. 5 is a section taken on the line 5-5 of Fig. 1, looking in the direction of the arrows. Fig. 6 is a detailed perspective view of the 35 sliding jaw.

30 Referring to the accompanying drawing by numerals it will be seen that the wrench comprises a shank 1 having a fixed jaw 2 formed upon one end thereof, while the opposite end terminates in the gripping portion 3. This shank 1 is provided with a longitudinal slot 4 adjacent the fixed jaw 2, and it is also provided with a plurality of rack 35 teeth 5 formed upon its rear side edge.

40 The sliding jaw comprises a body portion 6 having integral rearwardly extending side portions 7 which are constructed so as to extend in parallel spaced relations relative to each other. These sides 7 are provided with 45 registering apertures 8 and 9 through which the retaining bolts 10 and 11 are adapted to pass. These bolts 10 and 11 also pass through the longitudinal slot 4 formed in the shank 1 thereby positively retaining the 55 sliding jaw upon the shank 1 in such a man-

ner as to allow the same to easily slide thereon when necessary.

The adjusting lever 12 is provided, adjacent one end, with the gripping portion 13 which is adapted to the form so as to be adjacent the gripping portion 3 of the shank 1. The opposite end of this gripping lever 13 is bifurcated as shown at 14 so as to provide the ears 15. These ears 15 are adapted to fit 60 upon either side of the shank 1 thereby embracing the same, as clearly disclosed in Figs. 2 and 5. These ears are also provided with registering apertures 16 through which the bolt 11 passes for pivotally retaining 65 the lever 12 in an engagement with the movable jaw of the shank. This lever 12 is also provided with rack teeth 17 formed upon its inner portion and being so constructed as to come into engagement with rack teeth 5 of 70 the shank 1 when the lever 13 is swung toward the shank 1 as shown in Fig. 1. By referring particularly to Fig. 6 it will be seen that the inner portions of the side 7 of the sliding jaw 6 are notched as indicated at 75 18 whereby sufficient space is provided for the reception of the ears 15 of the adjusting lever 12.

When this wrench is in operation it will normally assume the positions disclosed in 80 Fig. 1. The adjusting lever 12 may then be swung away from the shank 1, causing the teeth 5 and 17 to become disengaged. At this time the adjusting lever 12 may move in either direction so as to slide the jaw 6 85 either toward an open or closed position as the occasion may require for providing sufficient space to accommodate the various sized nuts or bolt heads. When the right sized space is provided the gripping portion 13 of 90 the adjusting lever 12 may draw toward the gripping portion 3 of the shank 1, whereby the teeth 5 will be engaged by the teeth 17 as shown in Fig. 1. By continued gripping 95 action upon the gripping portions 3 and 13 100 the adjusting lever 12 will be held adjacent the shank 1 whereby the sliding jaw will be retained in an adjusted set position upon the shank 1. It is of course obvious that if so desired the ears 15 may be provided with 105 cut-out portions 19 so formed as to go into registry with the longitudinal slot 4 of the shank 1, as the adjusting lever 12 is swung. Therefore, a piece of wire may pass through these cut-out portions and through the longitudinal slot 4 whereby the device may be 110 used also as a wire cutter by swinging the

adjusting lever 12 in such a direction as to cause the cut-out portions 19 to move from registry with the slot 4 as shown in Fig. 1.

From the foregoing description it will be seen that a very simple and efficient wrench has been provided wherein the sliding jaw is adjustably mounted upon the shank so as to accommodate various size nuts, while the adjusting lever is so constructed as to move 10 in either direction for operating the sliding jaw, and then being swung so as to retain the sliding jaw in a set position.

What is claimed is:

In a wrench of the class described, the 15 combination of a shank having a fixed jaw, said shank provided with a longitudinal slot extending from a point adjacent said fixed jaw, rack teeth formed upon the rear side-edge of said shank, a sliding jaw mounted 20 upon said shank, said sliding jaw provided with enlarged parallel side portions embracing the side surfaces of said shank, each of said side portions being provided with a shallow internal notch adjacent its outer 25 end, whereby said notches will be formed in alinement with each other, means passing

through said side portions and said slot for slidably retaining said sliding jaw upon said shank, thereby preventing said sliding jaw from having pivotal movement, an adjusting lever having spaced ears embracing the side surfaces of said shank, said ears fitting within said internal notches, and pivotally engaging said means, whereby said lever will be retained in engagement with 30 said sliding jaw, said lever being provided with internal rack teeth, said lever being adapted to be swung so as to cause the teeth thereof to disengage or engage said rack teeth of said shank when it is desired to move 40 said sliding jaw or retain the same in a set position, said side portions of said sliding jaw being adapted to guard said ears of said lever, whereby said ears will be protected from injury when in use.

In testimony whereof I hereunto affix my signature in presence of two witnesses.

OLE H. MELLUM.
